US00D720182S

(12) **United States Design Patent**
Lim et al.

(10) **Patent No.:** US D720,182 S
(45) **Date of Patent:** ** Dec. 30, 2014

(54) **PANEL**

(71) Applicant: **Samsung Electronics Co., Ltd.**,
Suwon-Si (KR)

(72) Inventors: **Changae Lim**, Seoul (KR); **Soo Hyun Yoon**, Seoul (KR); **Seonju Lee**, Seoul (KR)

(73) Assignee: **Samsung Electronics Co., Ltd.**,
Gyeonggi-do (KR)

(**) Term: **14 Years**

(21) Appl. No.: **29/454,272**

(22) Filed: **May 8, 2013**

(30) **Foreign Application Priority Data**

Nov. 9, 2012 (KR) 30-2012-0053698

(51) **LOC (10) Cl.** **07-02**

(52) **U.S. Cl.**

USPC **D7/405**

(58) **Field of Classification Search**

USPC D7/350.1, 350.3, 350.4, 402, 405, 406;
219/756-758; 126/19 M, 21 A, 275 E

See application file for complete search history.

(57) **CLAIM**

We claim the ornamental design for a panel, as shown and described.

DESCRIPTION

The single view is a front view of a panel showing our new design; the details shown in broken lines form no part of the claimed design.

1 Claim, 1 Drawing Sheet

U.S. Patent

Dec. 30, 2014
